INVENTOR.

UNITED STATES PATENT OFFICE.

WILLIAM CHARLES BILHAM, OF SOUTHAMPTON, ENGLAND.

TIRE FOR WHEELS OF ROAD VEHICLES.

Application filed August 6, 1920, Serial No. 401,764. Renewed September 18, 1923.

(GRANTED UNDER THE PROVISIONS OF THE ACT OF MARCH 3, 1921, 41 STAT. L. 1313.)

To all whom it may concern:

Be it known that I, WILLIAM CHARLES BILHAM, a subject of the King of Great Britain, residing at 64 Shakespeare Avenue, Southampton, England, have invented an Improved Tire for Wheels of Road Vehicles (for which I have filed an application in Great Britain, Dec. 7, 1918, Patent No. 134,671); of which the following is a specification.

This invention relates to elastic tires for wheels of road vehicles, and has for its object to provide a resilient tire, the tread surface of which can be easily removed without interfering with the main body of the tire, or affecting the resiliency of same.

To the above end, the invention comprises a series of elastic rubber bands which are placed one above the other, the inner one resting upon the surface of the rim, the rim being of metal or other suitable material, and the bands being provided with spaced transverse blocks of rubber or the like secured to the bands and extending the entire width of the bands. The blocks may be any suitable shape and are preferably spaced apart a distance at least equal to the width of the blocks.

In constructing the tire, the bands are so arranged that, when pressure is applied to the tread of the tire, the blocks on each band are forced to bear between the blocks of the preceding band. Over the plain surface of the outermost band there is provided a strong band of canvas, leather, or other suitable material which forms the tread, and when the tread band is worn out and requires renewal, it may be readily replaced by a new one.

In action, all the blocks bear on the elastic portion of each preceding band, and thus provide a tire of great resilience.

Considering the functioning in relation to a single block of the outer series, when pressure is exerted thereon the block will tend to enter between the two adjacent blocks of the next succeeding series inwardly toward the rim, tending to force the intervening elastic band between said blocks, spreading them apart and forcing them toward the rim. Each of the two blocks so affected will tend to enter between the two adjacent blocks of next series and will in turn tend to force the intervening band be-

tween said blocks, spreading them apart. 55 In this manner when pressure is exerted on a block of the outer series it will be transmitted to two blocks of the intermediate series and from those two blocks to three of the next series, constantly widening the 60 base of support inwardly and insuring the outer block against tangential displacement due to the tractive thrust thereof against the road. This effectively prevents creeping of one band relative to another and 65 avoids the excessive heating which results from such relative movement. It also prevents excessive longitudinal stretching of the bands by distributing the strain over an ever widening area of said bands in the direction of the rim.

Having thus generally described the objects, nature and effects of the invention, I will now proceed to describe it with reference to the accompanying drawings which 75 show an example of a tire according to my invention. In the various figures the same parts are designated by the same letters, and they correspond with those used in the following explanation of the example. 80

Figure 1 is a longitudinal sectional view of a portion of a tire constructed according to the invention.

Figure 2 is a cross sectional view of a portion of the tire.

Figure 3 is a plan view of one of the intermediate bands of said tire.

With reference to the drawings, *a* designates the metal or other rim of the wheel, *b* denotes a band of rubber or similar elastic material which carries a series of blocks *c* of rubber or the like, and is sprung or fitted on the wheel rim *a*. Over the band *b* and blocks *c* there is sprung a band *b*¹ of rubber or similar elastic material which carries a series of blocks *c*¹, each of which overlies the space between a pair of the blocks *c* carried by the band *b* and over the band *b*¹ and blocks *c*¹ there is sprung a band *b*² of rubber or similar elastic material which carries blocks *c*², 100 each of which overlies the space between a pair of the blocks *c*¹ on the band *b*¹. Over this band *b*² and blocks *c*² there is sprung a plain band *b*³ of rubber or similar elastic material and over this there is fitted a band *d* 105 of leather or other suitable material which forms the tread band. The bands *b*¹ and *b*² as shown in the drawings are, for purposes

of illustration, shown as thicker in proportion to the blocks than they would be in actual practice.

Figure 3 shows in plan view the arrangement of the blocks c^1 on the band b^1 , and Figures 1 and 2 show in longitudinal and cross sectional views the respective positions of the bands b , b^1 , b^2 , with their respective blocks, the blocks being so arranged that, when pressure is exerted on the tread bands d and b^3 , the blocks c^1 , c^2 are forced respectively with the bands b^1 and b^2 more or less into the spaces between the blocks c and c^1 respectively.

It will be noted that in Figure 2, the tire is shown as having its sides converging toward the tread thereof. In this manner the bases of the layers are progressively decreased in width toward the tread of the tire thereby giving each succeeding layer progressing inwardly a wider base than the preceding layer. It will also be noted that the outer surface of the band b^3 , that is to say, the surface toward the tread of the tire, is slightly curved and that the inner surface of the tread member d is curved to conform with the curvature of the outer surface of the band b^3 , whereby the tread d is held against lateral displacement.

Having thus described my invention, what I claim as new therein, and desire to secure by Letters Patent is:—

1. A resilient tire for vehicles comprising an elastic band fitted about the rim of a

wheel, a tread surface spaced therefrom by 35 a plurality of alternate elastic bands and intervening series of resilient blocks, the blocks of the several series being spaced apart a distance at least equal to the width of the blocks in the next adjacent series and 40 located opposite the spaces between the blocks of said next adjacent series.

2. A resilient tire for vehicle wheels comprising a plurality of alternately superposed layers of elastic bands and layers of spaced 45 elastic blocks alternating therewith, the elastic blocks of each layer being spaced apart, a distance at least equal to the width of the blocks, the blocks of one layer lying opposite the spaces between the blocks of 50 the next adjacent layer.

3. A resilient tire for road vehicles comprising a plurality of concentric resilient bands, a plurality of annular series of transversely arranged spaced resilient blocks between said bands, the blocks of each of the several series being spaced apart so that the blocks of one series will lie opposite the spaces of the adjacent series, and a comparatively non-resilient removable tread for said 55 tire.

In testimony whereof I have hereunto set my hand in presence of two subscribing witnesses.

WILLIAM CHARLES BILHAM.
